UNITED STATES PATENT OFFICE.

LOUIS N. D. WILLIAMS, OF OGONTZ, PENNSYLVANIA.

UNITING KNITTED WEBS.

1,270,084.

Specification of Letters Patent. Patented June 18, 1918.

Application filed February 15, 1917. Serial No. 148,756.

To all whom it may concern:

Be it known that I, LOUIS N. D. WILLIAMS, a citizen of the United States, residing in Ogontz, Pennsylvania, have invented 5 certain Improvements in Uniting Knitted Webs, of which the following is a specification.

The object of my invention is to effect the attachment of the lip of a toe pocket to the 10 front end of the corresponding portion of the foot web of a stocking by the same machine upon which the said stocking is knitted, and by a continuation of the knitting operation whereby the toe pocket was produced. 15

This object I attain in the manner hereinafter set forth, reference being had to the accompanying drawings, in which—

Figure 1 is a vertical sectional view of 20 part of a circular knitting machine and of certain parts employed in combination therewith for the purpose of carrying out my invention in connection with the closing of the toe pocket of a stocking;

Figs. 2, 3 and 4 are vertical sectional views illustrating one of the needles of the set, upon which the toe pocket is to be knitted, and one of a series of retainers co-operating with the needles, Fig. 2 showing the 25 relation of the retainer to the needle during the formation of the initial or setting up course around the lip of the toe pocket, Fig. 3 showing such relation after the initial course has been completed, and the further 30 knitting of the toe pocket is about to begin, and Fig. 4 showing the relation of the parts after the knitting of the toe pocket has been completed;

Fig. 5 is a view similar to Fig. 3, but 35 showing the first stage of the operation of transferring the loops around the lip of the toe pocket to the needles which produce the corresponding portion of the foot web;

Fig. 6 is a view similar to Fig. 5, but 40 showing a further stage in such operation;

Fig. 7 is a view similar to Fig. 1, but 45 showing the final stage of the transfer operation;

Fig. 8 is a diagrammatic representation, 50 on an exaggerated scale, of needles and loop retainers of the machine illustrating said retainers in the relation to the needles shown in Fig. 3;

Fig. 9 is a representation of the loops 55 around the forward lip of the toe pocket,

and of the retainers therefor, in the relation to the transfer points shown in Fig. 5;

Fig. 10 is a representation of the needles of the machine, the transfer points and the loops around the forward lip of the toe 60 pocket in the relation to each other shown in Fig. 7;

Fig. 11 is a representation of the stitches of the toe pocket and of the initial course of the foot web, the latter stitches being 65 shown in their relation to the stitches of the final course of the toe pocket, and to the loops around the forward lip of the same.

In Fig. 1 of the drawing, 1 represents part of the needle cylinder of an ordinary 70 circular knitting machine having the usual spring or latch needles 2 and 2^a, the needles 2 extending around one-half of the cylinder and the needles 2^a around the other 75 half of the same. The machine is also provided with the usual web holders 3 which are mounted so as to reciprocate in a carrying ring 4 outside of the cylinder and are each actuated by a cam ring 5 which imparts such reciprocating movement thereto 80 in the ordinary manner.

Extending around that half of the cylinder which contains the needles 2 are a semi-circular series of loop retainers 6 which, in the present instance, have stems 6^a pivotally 85 mounted in a semi-circular carrier 7, which may be detachably mounted above the needle cylinder in any available way, said retainers 6 being under control of cams in a segment 7^a whereby they can be projected 90 and retracted as desired, and being preferably hooked, as shown, so as to prevent the knitting yarn or yarns applied thereto from slipping from the ends of the same.

In forming a toe pocket in accordance 95 with my invention I reverse the usual procedure, that is to say, instead of first completing the foot portion of the stocking, then putting out of action, but permitting to retain their stitches, those needles around the instep portion of the foot web, then knitting the toe pocket as a continuation of the sole portion of said web, and finally casting off the terminal stitches around the mouth of said pocket to be subsequently 100 united to the stitches around the front end of the instep portion of the web by means of a separately produced course of stitches in the usual way, I start the knitting of the stocking at the toe pocket, transfer the ini- 110

initial course of loops at the lip of the pocket to a set of retainers, then proceed to produce the toe pocket by reciprocating knitting, and narrowing and widening upon one-half of the needles of the machine in the usual manner, and, after the production of the pocket has been completed, transfer the loops from the retainers onto the naked needles of the other half of the machine, and then proceed with the formation of the foot tube, the result being that the lip of the toe pocket is knitted to the front end of the foot tube and the usual seam at this point is rendered unnecessary. With this object and this method of operation in view I proceed as follows:

During the application of the yarn to the needles 2 for the formation of the initial or setting up course of stitches around the forward lip of the toe pocket, the retainers 6 occupy the relation to said needles shown in Fig. 2, whereby, at the same time that the yarn is being engaged by the needles 2, it will be laid in the hooks of the retainers 6 and loops of said yarn will be held thereby.

Preferably, in starting to knit the toe pocket the yarn is first applied in one direction to alternate needles 2 of the set, for instance to those represented in black in Fig. 8, and on the return movement is fed to the needles 2 which alternate with those to which it was first fed, for instance, to those represented in white in Fig. 8. Between successive black needles, and also between successive white needles is thus interposed a pair of separated retainers 6.

The yarn is therefore applied to the retainers 6 during both its forward and its backward course, hence, as shown in Fig. 8, 40 yarn loops around the mouth of the toe pocket will have been laid upon each of said retainers, and, when the retainers are retracted, as shown in Fig. 3, prior to the feeding of the next course of yarn to all of the 45 needles 2, loops α will be disposed behind the black needles and loops α' behind the white needles.

The production of the toe pocket upon the needles 2 is then effected in the usual 50 manner, and when it has been completed it will be suspended between the needles 2 and retainers 6 in the manner shown in Fig. 4, the needles engaging the terminal course of the pocket and the retainers 6 engaging the 55 loops α , α' , around the forward lip of the pocket. The retainers are now projected to the position shown in Fig. 5 for co-operation with a semi-circular set of transfer points 8 whose stems are mounted radially 60 in a segmental carrier 9, either fixedly in the position shown in Fig. 5, or so as to be radially reciprocated in said carrier by means of a cam segment 10 in order to assume either a projected position, as shown 65 in Fig. 5, or a retracted position, as shown

in Fig. 1, the latter construction being preferred.

The retainers 6 being in the position shown in Fig. 5, the transfer points 8 and their carrier are raised so as to engage the 70 points with the loops α and α' , as shown in Fig. 9, the raising movement of the transfer points being continued until the yarn has been lifted free from the retainers 6, the latter being then retracted, as shown in Fig. 6, 75 prior to their removal from the machine along with their carrier 7 and cam segment 7a.

The transfer point carrier 9 and its points, with the loops of yarn upon them are now 80 swung from the position shown in Figs. 5 and 6 to that shown in Fig. 7, so as to apply the loops α to the black needles 2a and the loops α' to the white needles 2a around the other half of the machine, as shown in Fig. 85 10, and the transfer points are then withdrawn from the loops α , α' leaving the latter upon said needles 2a.

Round-and-round knitting is then proceeded with upon all of the needles for the 90 production of the foot web of the stocking, the stitches w of the first course around one-half of said foot web being interknitted with the terminal stitches w' of the toe pocket and the stitches y of the first course around the 95 other half of the foot web being interknitted with the loops α , α' around the forward lip of the toe pocket, as shown in Fig. 11, thereby forming an integral union of said lip with the corresponding portion of the foot 100 web and producing a closed toe upon the same machine upon which the toe web was knitted, and by a continuing operation.

The object in feeding the yarn first in one direction to one half of the set of needles to 105 be afterward employed in the production of the toe pocket, and then in the opposite direction to the alternating needles of the set, is to permit of the use of stitch transfer points in line radially with the needles, for when this method is adopted the yarn loops α , α' will each bridge a corresponding needle 2, and when the retainers 6 are projected, as shown in Fig. 5, the loops which were formerly behind the needles will be carried in 110 front of the same, and each of the transfer points 8 will engage with a loop which is in line with a corresponding needle wale of the toe pocket, as shown in Fig. 9, hence, after these loops have, as shown in Fig. 10, been 115 transferred to the needles 2a, and the knitting of the foot web is started, stitches y of the first course of said foot web will be drawn through said loops and will each register with a corresponding wale of the toe 120 pocket, as shown in Fig. 11.

If, on the other hand, the setting-up course was produced by carrying a single 125 yarn from one end of the set of needles 2 to the other and feeding said yarn alter- 130

nately to a needle and to a retainer 6, the transfer points would have to be disposed between the needles 2 in order to receive the loops from said retainers 6, and not only 5 would the loops be smaller and the engagement of the transfer points with said loops therefore more difficult than by the method first described but the transfer points, being out of register with the needles, would 10 have to be shogged laterally in order to bring them into register with the needles 2^a on the opposite side of the machine, and the transferred loops would be laterally deflected instead of in line with the corresponding 15 needle wales of the toe pocket.

I claim:

1. The mode herein described of effecting the production of a closed toe member upon a stocking knitted upon a circular knitting 20 machine, said mode consisting in forming a starting course for the toe upon the needles around one-half of the machine by feeding yarn first to every other needle of the set and to retainers adjacent thereto and then 25 to the other needles of the set and to said retainers, continuing the hold of the retainers upon the yarn during the formation of said toe member upon said set of needles, then applying the retained loops to the needles around the other half of the machine, and then continuing the knitting upon all 30 of the needles.

2. The mode herein described of effecting the production of a closed toe upon a stocking web, said mode consisting in engaging and retaining loops of the starting course of a toe pocket, continuing such retention during the formation of the toe pocket by reciprocating knitting upon one half of the 40 needles of the machine, then engaging transfer points with the loops and freeing the latter from the retainers, then by means of such transfer points applying the loops to the hitherto inactive needles of the machine, and then knitting the foot web upon all 45 of the needles.

3. The mode herein described of producing upon the needles of a knitting machine a closed toe upon the foot web of a stocking, said mode consisting in feeding the knitting yarn first to every other needle of one half of the machine and then to the needles alternating therewith, and during each feed forming loops of yarn which 50 bridge alternate needles, engaging said loops with retainers which continue such retention during the production of a toe pocket by reciprocating knitting upon the needles of said half of the machine, then

applying the loops so retained to the hitherto inactive needles of the other half of the machine, and then knitting the foot web upon the full set of needles. 55

4. The mode herein described of producing upon the needles of a knitting machine a closed toe upon the foot web of a stocking, said mode consisting in feeding the knitting yarn first to every other needle of one half of the machine and then to the needles alternating therewith, and during each feed forming loops of yarn which bridge alternate needles, engaging said loops with retainers which continue such retention during the production of a toe pocket by reciprocating knitting upon the 60 needles of said half of the machine, then discharging the loops from said retainers onto a set of transfer points, then delivering said loops from said transfer points to the hitherto inactive needles of the other 65 half of the machine, and then knitting the foot web upon the full set of needles.

5. The mode herein described of producing upon the needles of a knitting machine a closed toe upon the foot web of a stocking, said mode consisting in first engaging loops of the starting course of a toe pocket, then carrying said loops backwardly out of range of the needles upon which the toe 70 pocket is afterward produced by reciprocating knitting, and retaining them in such position during the formation of the toe pocket, then applying said loops to the hitherto inactive needles of the machine, and then knitting the foot web upon all of the 75 needles.

6. The mode herein described of effecting the production of a closed toe upon a stocking web, said mode consisting in engaging loops of the starting course of a toe pocket, 80 carrying said loops backwardly out of range of the needles upon which the production of the toe pocket is subsequently produced by reciprocating knitting, retaining the loops in such retracted position during the production of the toe pocket, and upon the completion of the same projecting the loops forwardly beyond the needles, then engaging each loop with a transfer point and releasing it from the retainer, then applying the 85 loops by means of the transfer points to the hitherto inactive needles of the other half of the machine, and then knitting the foot web upon all of the needles. 90

In testimony whereof I have signed my 95 name to this specification.

LOUIS N. D. WILLIAMS.
